UNITED STATES PATENT OFFICE

ARLEIGH N. VAN NOSTRAND, OF FLUSHING, NEW YORK, ASSIGNOR TO TELAUTOGRAPH CORPORATION, OF NEW YORK, N. Y., A CORPORATION OF VIRGINIA

CONTACT MAKER AND BREAKER

Application filed September 29, 1928. Serial No. 309,270.

This invention relates to improvements in circuit makers and breakers, and particularly to such an apparatus specially suitable or use in connection with telautograph transmitting apparatus.

In telautograph apparatus of the type requiring a direct current for operating the receiver from the transmitter it is sometimes necessary to obtain the electric energy from an alternating current source and then change this alternating current into a direct current through suitable apparatus, as, for example, by a rectifying device of the so-called vacuum tube type. In such telautograph systems it is desirable to have the rectifying apparatus in operation only when the telautograph apparatus is in actual use and, for the sake of convenience, as well as to avoid failures to shut off the current by oversight, it is very important to provide means whereby the operator in starting to operate the transmitter in the usual way will thereby, without any additional manual act, start the rectifying apparatus and when terminating the operation of the transmitter in the usual way will, also without any additional manual act, stop the rectifying apparatus.

The apparatus embodying the present invention is a circuit maker and breaker particularly advantageous for closing a circuit when the stylus of the telautograph is moved to unison position and for opening such circuit when the stylus is moved away from the unison position, the construction of the said circuit maker and breaker being such that it will act as a spring device to force the stylus away from the unison position and open the said circuit, if for any reason the stylus should be released by the operator when the said stylus is in the unison position. The circuit which is opened and closed in the present example serves as a control circuit for starting and stopping the rectifying apparatus.

By the present invention a circuit maker and breaker is provided which when open will have the contact points sufficiently separated so that arcing cannot occur even with relatively high voltages, and yet the relatively widely open contact points may be

brought in engagement by a relatively small movement of the stylus. Also a high degree of accuracy and durability is attained, so that the positions at which the stylus opens and closes the circuit may be fixed in initially 55 constructing and adjusting the apparatus and will not change materially in any reasonable time. In addition to this there is a relatively strong pressure between the contact points at the initial engagement as will 60 be more fully explained hereinafter, thereby insuring a sure closure of the circuit upon such initial contact.

While the subject matter of the invention is shown and described in relation to and 65 forming part of a telautograph transmitter it is highly advantageous for use in other situations where similar conditions are to be met.

The drawings illustrate an embodiment of 70 the invention for use with a telautograph transmitter.

In the drawings Fig. 1 is a plan view of the circuit maker and breaker, with some of the parts of a telautograph transmitter adjacent to the circuit maker and breaker.

Fig. 2 is a sectional view of the circuit maker and breaker, and

Fig. 3 a side elevation of the same.

Referring to the drawings, A indicates one 80 curved rheostat of the usual telautograph transmitter of the variable direct current type, B is the platen, C is the stylus, D is the unison switch, and E one of the operating rods connecting the stylus with one of the bell-crank devices, this bell-crank device serving to move a contact roller over its rheostat. The bell-crank device, above mentioned, comprises arms 3 and 4 suitably pivoted to 85 swing in a horizontal plane about an axis indicated at 5. The arm 3 carries the usual spring mounted roller 2 which rides over its rheostat A. All of these above mentioned parts are well-known elements in telautograph transmitters and hence need not be specifically described.

The circuit maker and breaker of the present invention is advantageously located at the right hand side of the rheostats, in which location it is arranged to be operated or actu- 100

ated upon movement of the right hand bell-crank to its extreme outward position, which occurs when the stylus is brought to the union position.

5 In the best embodiment of the invention as shown in the drawings, the circuit making and breaking device is as follows:

A suitable insulating support, in this case consisting of a block 11 of suitable insulating material, is secured to the transmitter frame. To the inner side of this block is secured a pair of contact spring devices and a pair of stop devices for said contact spring devices. The contact spring devices consist of a master contact spring 14 and a secondary contact spring 15, each having a contact point, as indicated at 21 and 22 respectively, these contact points being arranged to engage each other and being each provided with rounded faces. The master contact spring 14 comprises a clamping portion, an intermediate resilient portion and a stiffened outer end portion. The clamping portion of the spring 14 is provided with two holes for a purpose hereinafter described. The secondary contact spring 15 has a clamping portion provided with two holes, an intermediate resilient portion, and a stiffened hooked end as more fully explained hereinafter. The stop devices comprise a master contact spring stop device 19 arranged to limit the movement of the master contact spring 14, and a secondary contact spring stop device 20 to limit the movement of the secondary contact spring 15. Each stop device has a clamping portion provided with two holes for a purpose hereinafter explained, and also has a projecting arm to which the terminal of a circuit conductor may be secured, as for example, by soldering. In order to give sufficient rigidity to the stop devices 19 and 20 they may be made of relatively stiff or heavy material which is comparatively unyielding.

45 The stop device 19, for the master contact spring 14, is provided with an inturned end having an edge arranged to be engaged by the stiffened portion of the master contact spring, the latter being so formed that it will tend to press relatively strongly against said edge of the stop device 19. The stop device 20 for the secondary spring is so arranged that its free end will project into the hook of the stiffened hooked end of said secondary contact spring 15, and the latter is so formed that it has such a tendency to move toward the master contact spring 14 that the hooked end will press relatively strongly against its stop device 20. The stop devices 19 and 20 are so formed that when each is engaged by its respective contact spring, the contact points of said springs will be out of contact with each other and the circuit which includes them will be broken so that no arcing can take place across the

gap, the amount of separation of the contact points depending, of course, on the voltage of the circuit.

The contact springs and their stop devices are held in rigid relation by two screws, 12, 13, passing through the holes in the clamping portions of said springs and stop devices, and by bushed insulating washers. The bushed insulating washers comprise intermediate washers 16 and outer washers 18. The washers 16 are located between the contact springs, and have their bushings extended through the holes in the secondary contact spring 15 and into those in its stop device. The outer washers 18 are located outside the stop device 19 and have their bushings extended through the holes in the stop device 19 and into those in the master contact spring. The portions of the screws 12 and 13 projecting beyond the bushed insulating washers 18 are provided, next to the said washers 18 with metal washers 26; also with spring locking washers 27 next to the metal washers 26, and with nuts 17 outside the locking washers. When the nuts 17 are screwed up firmly the contact springs and their stop devices are clamped firmly in proper relation to each other and are rigidly secured to the insulated mounting-block 11. Each contact spring is in electrical contact with its stop device as will be clear from the drawings.

Reference has been made heretofore to the stiffened lever portion of the master contact spring 14. While this stiffening may be accomplished in various ways, it has been found satisfactory to accomplish this by providing the contact spring with ribs or flanges along its edges. In practice it is advantageous to have these ribs or flanges extend from the free end of the contact spring 14 inward toward the clamped end of the spring far enough to include all or nearly all of the contact point 21 within the ribbed or flanged portion. The stiffened portion of the master contact spring extends beyond its stop device and beyond the secondary contact spring, so as to be in the path of movement of the actuator 7 which is carried by the arm 3 of the bell-crank.

The hooked end of the secondary contact spring may be stiffened in any suitable way. One simple way is to form ribs or flanges on the hooked portion, as indicated at 23.

The result of stiffening the free end of the master contact spring 14 is to confine all bending of the spring to the resilient portion which extends between the stiffened portion and the clamping portion, the latter being held rigidly by the screws and washers. As the stiffened portion of the master contact spring rests against its stop device 19 the actuator 7 will encounter the master contact spring and begin to move the latter always at the same angular position of the bell-crank and the amount of such movement is

substantially in direct proportion to the movement of the actuator. As the space between the contacts 21 and 22 in the resting, open position of the contacts is determined 5 in part by the stiffened hook end of the secondary contact spring which is in engagement with its stop device 20, this space is always constant because of the substantially unyielding nature of such hook and stop device. 10 Hence the angular movement of the bell-crank and its actuator necessary to bring the two contacts 21 and 22 into engagement and close the circuit is substantially invariable. Thus, it is possible to obtain great accuracy 15 of setting and of operation so that only a relatively small angular movement of the bell-crank arm 3 is required to close the control circuit for starting the rectifying apparatus while giving a relatively large gap or break 20 between the contact points. In order to maintain the same writing space at the transmitter free of any mechanical resistance due to action of the springs of the contact maker and breaker the unison switch at the transmitter is located slightly further away from 25 the platen, usually about one-fourth inch more than before, this allowing for the additional movement of the stylus necessary for the operation of the circuit maker and breaker. 30

In order to stop the outward movement of the bell-crank arm 3, a fixed stop device is provided. In the present example this consists of a stop-plate 25 provided with a 35 flanged outer end to contact with the bell-crank arm 3, the stop-plate 25 being secured to the block 11 by suitable means, such as the screws shown in the drawings. It is to be noted that the stop-plate is so located that it 40 will stop the bell-crank arm 3 shortly after this arm has brought the contact points 21 and 22 into engagement with each other and before the secondary contact spring 23 can touch the stop-device 20. This avoids unnecessary straining of the contact spring 23, 45 yet insures a positive engagement of the two contact points 21 and 22. If the stylus should be released by the operator when the contact points are still in engagement, the 50 contact springs will serve to force the bell-crank arm and the stylus out of the unison position and will open the circuit by separating the contact points. The master contact spring 14 principally accomplishes this movement, but of course is assisted in starting the 55 movement by the resiliency of the secondary contact spring 15 which follows the movement of the master contact spring 14 until stopped by the hooked end engaging the stop device 20 after which the master contact 60 spring 14 moves toward its own stop device 19 until its stiffened portion rests firmly against the edge of the outer end of the stop device 19. 65 It is an important advantage of the inven-

tion, that because the contact springs 14 and 15 are separated considerably, their contact points swing in different arcs, thus giving a wiping or rubbing action of the contacting faces of said contact points after they have made a contact. This wiping action is sufficient to maintain the contact faces clean. 70

The actuator 7 mounted on the bell-crank 3 may be a disk of any relatively hard insulating material held to the bell-crank 3 by a 75 screw or rivet as shown.

It is to be noted that by giving the secondary contact spring 15 such a set that it will press strongly against its stop device 20, an equivalent pressure will be necessary, 80 acting against the contact point of such secondary contact spring, to force the latter away from its stop device. Therefore, when the master contact point of the contact switch initially engages the coacting contact point of the secondary contact spring, 85 a relatively heavy contact pressure is developed before the secondary contact spring starts its movement. This insures a low resistance at the contact faces and a certain closure of the circuit at the predetermined position of the bell-crank arm and its actuator, which would not be true if the secondary contact spring was easily displaced from its 90 normal position. 95

What I claim is:

1. In a circuit maker and breaker, the combination, with a pair of stop devices, each arranged to be connected to one terminal of an electric circuit, a master contact spring tending to press against the adjacent one of said stop devices, a secondary contact spring provided with a hooked end into which the free end of the other stop device enters, said secondary contact spring tending to press its hooked end against its stop device, said contact springs being located between said stop devices and provided with contact points facing each other and normally out of contact with each other when the contact springs are stopped by their respective stop devices, each contact spring being in electrical communication with its respective stop device, means for holding said contact springs and their respective stop devices with the springs separated from each other at the holding means, and an actuator arranged to engage the master contact spring and move it into contact with the secondary contact spring and to move the latter toward its stop device, the master contact spring serving to return the actuator and open the circuit through the contact points when the actuator is released. 110 115

2. In a circuit maker and breaker, the combination, with a pair of stop devices, each arranged to be connected to one terminal of an electric circuit, a master contact spring tending to press against the adjacent one of said stop devices, said master contact 120 125

spring being provided with a stiffened free end, a secondary contact spring provided with a hooked end into which the free end of the other stop device enters, said secondary contact spring tending to press its hooked end against its stop device, said contact springs being located between said stop devices and provided with contact points facing each other and normally out of contact with each other when the contact springs are stopped by their respective stop devices, each contact spring being in electrical communication with its respective stop device, means for holding said contact springs and their respective stop devices with the springs separated from each other at the holding means, and an actuator arranged to engage the stiffened free end of the master contact spring and move said spring into contact with the secondary contact spring and to move the latter toward its stop device, the master contact spring serving to return the actuator and open the circuit through the contact points when the actuator is released.

3. In a circuit maker and breaker, the combination, with a pair of stop devices, each arranged to be connected to one terminal of an electric circuit, a master contact spring tending to press against the adjacent one of said stop devices, a secondary contact spring provided with a hooked end into which the free end of the other stop device enters, said secondary contact spring tending to press its hooked end against its stop device, said contact springs being located between said stop devices and provided with contact points facing each other and normally out of contact with each other when the contact springs are stopped by their respective stop devices, each contact spring being in electrical communication with its respective stop device, means for holding said contact springs and their respective stop devices with the springs separated from each other at the holding means, an actuator arranged to engage the master contact spring and move it into contact with the secondary contact spring and to move the latter toward its stop device, the master contact spring serving to return the actuator and open the circuit through the contact points when the actuator is released, and means for limiting the movement of the actuator in closing the circuit through the contact springs.

4. A master contact spring and a secondary contact spring each having contact points, the master contact spring tending to move away from the secondary contact spring, and the latter tending to move toward the master contact spring, a stop device for limiting the movement of the secondary contact spring toward the master contact spring, against which stop device the secondary contact spring in its normal posi-

tion presses strongly, a stop device for limiting the movement of the master contact spring away from the secondary contact spring, said stop devices being arranged to stop their springs with their contact points separated sufficiently to open the circuit, an actuator arranged to move the master contact spring toward the secondary contact spring and to carry the latter away from its normal position, and means for limiting the movement of the actuator in its contact-closing direction.

5. A master contact spring and a secondary contact spring each having contact points, the master contact spring tending to move away from the secondary contact spring, and the latter tending to move toward the master contact spring, the master contact spring having a projecting stiffened end, a stop device for limiting the movement of the secondary contact spring toward the master contact spring, against which stop device the secondary contact spring in its normal position presses strongly, a stop device for limiting the movement of the master contact spring away from the secondary contact spring, said stop devices being arranged to stop their springs with their contact points separated sufficiently to open the circuit, an actuator arranged to engage the projecting stiffened end of the master contact spring to move it toward the secondary contact spring and to carry the latter away from its normal position, and means for limiting the movement of the actuator in its contact-closing direction.

In testimony whereof, I have hereunto set my hand.

ARLEIGH N. VAN NOSTRAND.
